UNITED STATES PATENT OFFICE.

ISAAC L. BAUMAN, OF LANCASTER, PENNSYLVANIA.

DESIGN FOR A COASTER.

45,366.

Specification for Design.

Patented Mar. 10, 1914.

Application filed December 12, 1913. Serial No. 806,333. Term of patent 3½ years.

To all whom it may concern:

Be it known that I, ISAAC L. BAUMAN, a citizen of the United States, residing at Lancaster, in the county of Lancaster and State of Pennsylvania, have invented a new, original, and ornamental Design for a Coaster, of which the following is a specification, reference being had to the accompanying drawing, forming part thereof.

The figure is a perspective view of the coaster illustrating my new design.

I claim:

The ornamental design for a coaster, as shown.

ISAAC L. BAUMAN.

Witnesses:

CHAS. E. LONG,
JOHN J. THOMPSON.
